CHARLES ROBERGE, OF WILLIAMSBURG, MASSACHUSETTS, ASSIGNOR TO PURO SANITARY DRINKING FOUNTAIN COMPANY, A COPARTNERSHIP OF MASSACHUSETTS, CONSISTING OF CHRISTIAN J. HILLS AND REUBEN B. HILLS, OF HAYDENVILLE, MASSACHUSETTS

DRINKING FOUNTAIN APPARATUS

Application filed January 14, 1931. Serial No. 508,710.

This invention relates to improvements in drinking fountain apparatus and is directed more particularly to improvements in heads and water discharging devices of drinking fountain apparatus.

According to the principal object of the invention, a drinking fountain head is provided which has associated therewith a nozzle or tip for discharging water from the head which is constructed and arranged to discharge a uniform stream. That is to say, the nozzle or tip is arranged to function for uniform discharge without regard to variations in the pressure of the water supply. According to special features of the invention the apparatus is adapted, when pressure in the system varies to deliver a predetermined amount of water and to discharge any excess into a discharge chamber with which the head is provided.

Various novel features and advantages of the invention and the mode of operation will be more fully hereinafter referred to in the accompanying description of the preferred form of the invention, which for purposes of disclosure is illustrated in the accompanying drawing wherein:

Fig. 1 is a side elevational view of a drinking fountain embodying the novel features of the invention.

Fig. 2 is a plan view of the drinking fountain head shown in Fig. 1, and

Fig. 3 is a longitudinal sectional elevational view through the nozzle or tip shown in Fig. 1.

Fig. 4 is a view similar to Fig. 1 showing a modified form of the invention.

Referring now to the drawing in detail, the invention will be described more fully.

As shown in Fig. 1, a drinking fountain head 2 is provided which may be generally in the form of a crescent. This head 2 consists of side walls 4, a lower or rearward wall 6, and joined together walls 8 and 10. These walls are joined together to form a chamber 9 which has a discharge outlet 18 at the lower end of the head. The upper end of the wall 10 and the upper end of the rear wall 6 are joined together at the upper side of the head to provide a portion 12 joined to cheeks 14

to form what may be called a cowl 16 at the upper side of the head. As will be seen in Fig. 2, the walls are curving at the upper cowl portion of the head and the discharge orifice 18 is provided in the upper side of the walls within the cowl.

A nozzle or tip 20 is as shown secured in some suitable manner in the head and a fitting 22 is screwed into the head below the tip. This receives a water supply pipe 24 by which pipe the head may be supported if desired. Of course the head may be supported in other ways.

Water enters the supply pipe 24, passes through the nozzle or tip 20 and is discharged thereby forwardly and upwardly through the orifice 18 and through the cowl in the direction of the arrow shown.

It will be appreciated that when a head of this type is connected to a water system that the pressure in the system is likely to vary. That is, at times the pressure is relatively greater or less than at others and accordingly the stream of water discharged by the nozzle or tips would ordinarily likewise vary.

It is to overcome this varying tendency of the stream discharged that certain novel features of the invention are directed. To accomplish this the nozzle 20 is hollow and has a plug 32 reciprocable therein. A cap 34 is provided in the outer end of the nozzle to limit the upward or outward movement of the plug.

One or more side openings 30 are provided in the lower side of the nozzle and bores 33 and 35 are provided in the plug 32 and cap 34 as shown. These bores may be of any desired size and will be preferably of some appreciable length so that water passing through them will be discharged from the nozzle in a smooth stream which is of course desirable.

It is usual in connection with such devices to provide a control valve in the line, such as 24, supplying water to the head so that the nozzle will discharge a predetermined amount of water. Such a control however is not adequate to compensate for variations in pressure which effect the stream discharged. According to the mode of op-

eration of the nozzle of the invention, in order to compensate for pressure variations or increase of pressure in the system will cause the plug 32 to be elevated. It will of course be elevated more or less according to the degree of increase of pressure. When the plug is thus elevated from its seat water will be discharged through the outlets 30 into the chamber 9 of the head. In this way 10 excess pressure or additional pressure is relieved without affecting the stream being discharged by the nozzle or tip. Therefore the pressure may fluctuate more or less and excess water accommodated while the stream 15 discharge may remain constant and uniform, as is desired. Excess water will find its way through the outlet 18 of the head.

The lower side of the plug 32 may have 20 a tapering seat as is indicated at 31 so that it will be under the influence of pressure conditions prevailing. In that way it is very sensitive to any fluctuation in pressures all to the end that the stream being discharged by the nozzle will remain constant 25 and any excess water will be discharged into the waste chamber.

Normally the plug 32 will rest on its seat and substantially all of the water delivered to 30 the nozzle will pass through the discharge bores 33 and 35. The valve controlling water delivered to the head will be set to accomplish this, but as stated if for any reason the pressure in the system increases then the 35 plug operates to allow the escape of surplus water to thereby maintain the desired uniformity of the discharge by the tip upwardly through the orifice and between the cheeks or through the cowl of the head.

The modification of the invention shown 40 in Fig. 4 will now be described.

In this form of the invention a head 40 is formed to have an inner chamber 42 as in the former case. An upper wall 44 is provided with an orifice 46 and a lower hub 48 45 receives a water supply pipe 49.

A nozzle 50 is provided to extend into the chamber and may be held in place by a threaded part 51 screwed into the hub. This nozzle is disposed in a vertical relation and 50 a discharge nipple 52 in the form of a tube extends from the upper or discharge end thereof in an angular relation. This nipple 52 is arranged to discharge water upwardly 55 through the orifice as in the former case and as is indicated by the arrow in Fig. 4.

By arranging the parts so that the cowl 60 extends beyond the orifice water will not drip from the cowl through the orifice or from around the orifice onto the nozzle. By 65 directing the stream in an angular relation it is convenient to drink from a fountain employing the head.

The nozzle may take various forms but in 70 all cases it will preferably consist of relatively movable parts one of which is acted on and

under the influence of pressure prevailing in the system, so as to release excess pressure. The lower side of the plug is to be made so that its action is dependent on the pressure but need not necessarily have the tapering bore. 70 The nozzle or tip may be secured within the head in any suitable manner, but in the forms of the invention shown it is provided with a threaded lower shank portion 28 which screws into a suitable threaded opening in 75 the head.

Various changes may be made in the form of the invention without departing from the spirit and scope of the invention, therefore I wish to be limited, if at all, by the following claims rather than by the foregoing description. 80

What I claim is:

1. A drinking fountain apparatus comprising in combination, a hollow nozzle having an outlet in a side thereof, a cap in the upper side of said nozzle and a plug movable therein, the said plug and cap being provided with bores therethrough. 85

2. A drinking fountain apparatus comprising in combination, a nozzle having a central bore and a discharge opening in a side thereof, a cap in the upper end of said bore having an axial opening therein, a plug in said bore movable past 90 the opening in the side of the nozzle and being provided with a central bore. 95

3. A drinking fountain apparatus comprising in combination, a nozzle having a central bore therethrough and a discharge 100 opening in a side thereof adjacent its lower end, a plug in said bore provided with a central bore which is reciprocable in said bore of the nozzle to open and close said opening and the lower end of said plug and 105 the said nozzle below said opening being provided with coacting seating surfaces.

4. A drinking fountain apparatus comprising in combination, a nozzle having a central bore therethrough and a discharge 110 opening in a side thereof adjacent its lower end, a plug reciprocable in said bore of the nozzle having a central bore, a seat associated with the bore of said nozzle adjacent the lower side of said opening on which the lower 115 end of said plug may seat and the lower end of the bore in said plug being enlarged.

In testimony whereof I affix my signature.

CHARLES ROBERGE.
